[57] CLAIM

The ornamental design for an electronic cuff for stimulation, as shown and described.

DESCRIPTION

FIG. 1 is a perspective view of an electronic cuff for stimulation, showing our new design, in open condition; FIG. 2 is a left elevational view thereof; FIG. 3 is a right elevational view thereof; FIG. 4 is a front elevational view thereof; FIG. 5 is a bottom plan view thereof; FIG. 6 is a back elevational view thereof; FIG. 7 is a top plan view thereof; and, FIG. 8 is a perspective view thereof in use condition, the broken line showing of the leg being for illustrative purposes only and forming no part of the claimed design.
